UNITED STATES PATENT OFFICE.

ALLEN A. BOWSER, OF FORT WAYNE, INDIANA, ASSIGNOR TO S. F. BOWSER & CO. INC.,
OF FORT WAYNE, INDIANA, A CORPORATION OF INDIANA.

CAN-FILLING PUMP.

1,052,033.

Specification of Letters Patent.

Patented Feb. 4, 1913.

Application filed April 29, 1907. Serial No. 370,994.

To all whom it may concern:

Be it known that I, ALLEN A. BOWSER, a citizen of the United States, residing at Fort Wayne, in the county of Allen and 5 State of Indiana, have invented certain new and useful Improvements in Can-Filling Pumps, of which the following is a specification.

Heretofore in handling or dispensing 10 heavy oils or liquids, considerable difficulty has been experienced in that the air coming in contact with the wall of the pump cylinder will cause the liquids to adhere thereto and become hard and dry, thereby not only 15 reducing the diameter of the cylinder but causing the piston to work hard and with considerable difficulty.

To overcome this difficulty and serious objection and to provide means for preventing 20 the caking or hardening of the oils or liquids on the wall of the pump cylinder is the primary object of this invention.

A further object is to provide improved 25 means for always maintaining the pump cylinder full of liquid so long as there is sufficient liquid in the tank from which the liquid is dispensed.

A further object is to provide an improved 30 pump of this character which will be simple, cheap and durable in construction and efficient and effective in operation.

To the attainment of these ends and the accomplishment of other new and useful 35 objects, as will appear, the invention consists in the features of novelty in the construction, combination and arrangement of the several parts hereinafter more fully described and claimed and shown in the accompanying drawings, illustrating an exemplification of the invention and in which—

Figure 1 is an elevation of an improved 40 pump constructed in accordance with the principles of this invention. Fig. 2 is a sectional view on line 2—2 of Fig. 1. Fig. 3 45 is a sectional view on line 3—3 of Fig. 2. Fig. 4 is a sectional view on line 4—4 of Fig. 2.

Referring more particularly to the drawings and in this exemplification of the invention, the numeral 10 designates a supporting base which is provided with a chamber 11 opening through the top thereof, and an inlet opening 12 extending through the bottom thereof and communicating with the 50 chamber 11. The base 10 is preferably 55

provided with supporting legs or members 13 for holding the same elevated above the support upon which the base rests. The base is also provided with a discharge opening 14 in the upper face thereof and a passage 15 which forms a communication between the chamber 10 and the discharge opening 14. A suitable valve 16 is arranged within the chamber 11 to form a closure for the inlet opening 12 and said valve is held from displacement in any desired or suitable manner, preferably by means of a stem 17 which passes through a supporting web 18 arranged in the inlet 12 and said stem is preferably provided with a threaded extremity which engages the valve 16 on one side of the web 18 and a head 19 on the other side of the web so that when the valve is unseated, the head 19 will engage the web 18 and prevent the valve from being accidentally displaced.

The chamber 11 is preferably provided with a shouldered portion 20, upon which the end of a suitable cylinder 21 is adapted to rest and said cylinder is preferably of a configuration similar to the configuration of the chamber 11 and of a diameter substantially equal to the diameter of said chamber.

A suitable head 22 is provided with a chamber 23, which opens through one face of the head and said head is adapted to rest upon and be supported by the free extremity of the cylinder 21 in such a manner that the cylinder 21 will communicate with the chamber 23 therein. The head is also provided with a discharge outlet 24, which opens through the same face of the head, and the chamber 23 has communication with the discharge outlet 24 through the medium of a suitable passage 25. A discharge pipe 26 is connected by one end to the discharge outlet 24 in any desired or suitable manner, preferably by means of screw threads as shown, and said discharge pipe 26 extends toward the base 10 and terminates at a point slightly above the base of the supporting legs 13, so that when the pump cylinder is placed within the tank 27 so that the supporting legs 13 rest upon the bottom 28 thereof, the free extremity of the discharge pipe will terminate short of the bottom 28 of the tank. The head 22 and base 10 are secured together to prevent displacement of the cylinder 21 in any desired or suitable manner, preferably by means of 105 110

rods or bolts 29, which are provided with heads 30 and said rods or bolts 29 pass through suitable ears or projections 31 on the head 22 and the free extremities of said rods or bolts are preferably screw threaded as at 32 and are adapted to be seated in suitable threaded apertures in the base 10 and when in position the heads 30 will rest upon the ears or projections 31 and by seating the threaded extremities 32 in their respective apertures, the parts will be firmly clamped together.

The discharge opening 14 is preferably provided with interior screw threads 33 and located within the opening is a valve seat 34, which is preferably provided with a peripheral flange 35 and said valve seat 34 is adapted to be held in position in any desired or suitable manner preferably by means of a coupling member 36, which is provided with an exterior threaded extremity adapted to enter the discharge opening 14 and rest upon the flange 35 of the valve seat. The diameter of the extremity of the coupling member 36 is of such a size that the threads thereon will engage the threads in the discharge opening 14. A suitable gravity valve 37 is adapted to coöperate with the valve seat 34 and said valve 37 is preferably of a construction similar to the construction of the valve 16. Connected with the coupling member 36 is a reducer member 38 and connected with said reducer member 38 is a discharge pipe 39, the upper extremity of which projects above the top of the tank 27 and secured to said extremity is a faucet 40, the specific construction of which forms no part of the present invention.

If desired, a valve seat 41 and valve 42, similar in construction to the valve seat 34 and the valve 37, may be arranged between the coupling member 36 and the reducer member 38 and may be held in position by means of the reducer member 38 engaging the peripheral flange 43 of the valve seat.

The upper extremity of the discharge pipe 39 may be supported in any desired or suitable manner, preferably by means of a bracket or support 44, which is secured to a base 45, the latter being adapted to rest upon and be secured to the top 46 of the tank, so that when the cylinder 21 is placed within the tank, the support 45 will rest upon the top 46.

A suitable piston is adapted to move within the cylinder 21 and said piston preferably comprises a body portion 47, having a centrally disposed and upwardly opening recess or chamber 48. A piston rod 49 is provided with an enlargement or head 50 on one extremity thereof and said extremity, together with the head or enlargement 50, is adapted to be seated within the recess or chamber 48. This recess or chamber 48 is preferably provided with interior screw

threads and surrounding the piston rod 49 is a sleeve or collar 51, which is provided with peripheral screw threads and said sleeve or collar is adapted to be seated in the recess or chamber 48 and is of such a diameter that the peripheral screw threads thereon will engage the screw threads in the recess or chamber 48 to secure the piston rod and piston together.

The body portion of the piston 47 is preferably of a diameter considerably smaller than the diameter of the cylinder and said body portion is provided with a peripheral flange 52, which is of a diameter only slightly smaller than the diameter of the cylinder 21. A suitable flexible member 53 is supported by the piston head 47 so as to surround the piston rod 49 and is of a diameter somewhat larger than the diameter of the cylinder 21, so that when the flexible member is in position, the periphery thereof will engage and be bent downwardly by the wall of the cylinder. This flexible member is held in position preferably by means of a plate 54 which surrounds the piston rod 49 and is itself held in position preferably by means of a nut or collar 55 adjustably mounted upon the sleeve 51. A flexible member 56, such as a coil spring or the like, surrounds the body portion of the piston head 47 and rests upon the flange 52 so as to engage the periphery of the flexible member 53 to hold the latter yielding in engagement with the wall of the cylinder 51 as the piston is reciprocated.

The piston rod 49 passes through the head 22 and is preferably surrounded by a tubular member 57, one end of which is secured to the head 22 and the other end to the support 45. The piston may be reciprocated in any desired or suitable manner, preferably by means of a crank 58, which is connected to a suitable pinion gear (not shown) the latter being adapted to engage a suitable rack member 59 carried by the piston rod 49 so that the operation of the crank will move the piston.

If desired, a suitable screen 60 may be provided to surround the base 10 and said screen may be constructed of any suitable reticulated material, such as wire gauze or the like, and is preferably provided with an imperforate bottom 61. This screen is for the purpose of preventing foreign matter from entering the cylinder 21 and may be held in position in any desired or suitable manner, preferably by means of a screw or bolt 62, which passes through the imperforate bottom and may be seated in one of the legs 13, as shown more clearly in Fig. 4 of the drawing.

In operation, the cylinder together with its associated parts, is placed within the tank 27 so as to rest upon the bottom 28 thereof, and with the support 45 resting

upon the top 46 of the tank, which will permit the crank handle 58 and the discharge nozzle 40 to extend above the top of the tank. The tank being filled with oil, the 5 crank handle 58 may be rotated from the position shown in Fig. 1 of the drawing to the left, which will raise the piston 47 to the top of the cylinder 21. This movement of the piston will cause a suction within the 10 cylinder 21 to seat the valves 37, 42 and at the same time unseat the valve 16 and draw the liquid into the cylinder through the screen 60 and inlet 12. When the piston has reached the limit of its upward movement, which movement may be regulated by 15 suitable adjustable stops 63 and a co-operating stop 64 on the rack member 59, the handle 58 may be rotated in the opposite direction, causing the piston 47 to descend. 20 The pressure exerted upon the liquid in the cylinder as the piston descends will seat the valve 16 and force the liquid below the piston 47 through the passage 15, to unseat the valves 37, 42, which will permit the liquid 25 to pass through the discharge opening 14 into the discharge pipe 39 and out through the faucet 40 when the latter is open. During the descent of the piston 47, a suction 30 will be created in the cylinder above the piston 47, which will draw a quantity of the liquid from the tank into the cylinder through the pipe 26 and passage 25, thereby filling the cylinder above the piston. Upon the reverse movement or during the 35 ascent of the piston, the liquid which has been drawn into the upper portion of the cylinder will be discharged back into the tank through the passage 25 and pipe 26; a suitable bushing or packing 65 being provided to prevent the liquid from passing out through the tubular member 57. Thus it 40 will be seen that a reciprocating motion of the piston 47 will impart a churning motion to the liquid into and out of the top part of the cylinder, thereby maintaining the upper portion of the cylinder full of liquid to prevent the air from coming in contact with the wall of the cylinder, while the liquid, which has been drawn into the 45 cylinder through the inlet opening 12 and

which has not yet been discharged from the cylinder, will prevent the air from coming in contact with the wall of the cylinder below the piston.

In order that the invention might be fully 55 understood by those skilled in the art, the details of the foregoing embodiment thereof have been thus specifically described, but

What I claim as new therein and desire to secure by Letters Patent is—

1. In a pump the combination of a cylinder, a piston reciprocable therein, means for operating the piston, a valve controlled intake duct communicating with the source of supply at one end of the cylinder, a valve controlled discharge orifice at the same end of the cylinder with the intake duct, and a suction pipe communicating with the cylinder on the opposite side of the piston, said suction pipe communicating with the source of supply of the pump and forming an inlet and outlet cylinder adapted to receive liquid from the supply to discharge the same into the cylinder on the other side of the piston. 65

2. In a pump the combination of a cylinder, a piston reciprocable therein, means for operating the piston, a valve controlled intake duct communicating with the source of supply at one end of the cylinder, a valve controlled discharge orifice at the same end 75 of the cylinder with the intake duct, and a suction pipe communicating with the cylinder on the opposite side of the piston, said suction pipe communicating with the source of supply of the pump and forming an inlet 80 and outlet to the cylinder adapted to receive liquid from the supply to discharge the same into the cylinder on the other side of the piston, the inlet of the suction pipe from the source of supply being disposed in close proximity to the level of the intake duct. 85

In testimony whereof I have signed my name to this specification, in the presence of two subscribing witnesses, on this 23rd day of April, A. D. 1907.

ALLEN A. BOWSER.
